UNITED STATES PATENT OFFICE.

GUSTAV KORNGIEBEL, OF KASSEL, GERMANY.

REGULATOR FOR THE MOVEMENTS OF AIR OR SMOKE IN FLUES.

Application filed March 31, 1921. Serial No. 457,547.

This invention relates to a draft regulator to be inserted into channels for regulating the air draft or in flues for regulating the movement of the flue gas and it consists of a hollow body to be inserted into a channel or flue. The open end of this hollow body is closed by a plate which is exposed to the atmospheric pressure and suspended from one end of a pivotally counterweighted lever 10 arranged outside the hollow body. The inner surface of this freely suspended regulating plate is exposed to the action of the draft in the channel or flue, or to an auxiliary draft produced by air blown in, or by 15 both, the normal draft and the auxiliary draft.

The invention will be best understood from a consideration of the following detailed description taken in connection with 20 the accompanying drawings forming a part of this specification, with the understanding that while on the drawings several embodiments of the invention are disclosed, the invention is not confined to any strict conformity with the showing of the drawings, but 25 may be embodied in any manner which does not make a material departure from the salient features of the invention.

In the drawings:-

Fig. 1 shows in perspective view the hollow body and the draft regulating plate.

Fig. 2 is a longitudinal section of Fig. 1.

Fig. 3 shows in longitudinal section, a modified form of construction of the hollow body.

Fig. 4 shows, on a larger scale, the end of the counterweighted lever attached to the regulating plate.

Fig. 5 shows, on a larger scale, the pivotal 40 mounting of the counterweighted lever.

The hollow body 4 of the draft regulator is inserted in the air channel or in the flue by means of two horizontal tubular sockets 11, 12 as shown in Figs. 1 and 2 or in an 45 other manner as will be hereafter described. In the bottom of the hollow body a tubular socket 14 is arranged. Whether the tubular sockets 11 and 12 are closed or left open or whether one of the tubular 50 sockets 11 and 12 and the horizontal tubular socket 14 is used depends on whether the flue into which the draft regulator is to be inserted is straight or bent at right angles. The tubular socket which is not used is 55 closed and in Fig. 1 of the drawing the tubular socket 14 is shown closed by a lid 15.

In the open top end of the hollow body 4 a regulating plate 1 is movably mounted, said plate being freely suspended from the inner end of a pivoted counterweighted lever 2, 3. This lever 2, 3 is fulcrumed at 8 on an arm 27 upwardly extending from the upper part of the hollow body 4. The upper part 16 of the hollow body 4 may have the shape of a truncated cone as shown in Figs. 60 1 and 2. The end of the inner arm 2 of the counterweighted lever is preferably hook-shaped and engages with a lug 7 upwardly projecting from the regulating plate 1. On the outer arm 3 of the pivoted lever 70 a counterweight 6 is adjustably mounted. The regulating plate 1 which is suspended from the lever 2, 3 is adapted to be moved into the hollow body 4 under the action of the atmospheric pressure to which it is freely 75 exposed.

The point for suspending the regulating plate 1, the point at which the counterweight 6 acts upon the arm 3 of the pivotal lever 2, 3 and the fulcrum 8 of this lever are situated on a straight line as indicated in Fig. 3 by dash and dot lines. The fulcrum 8 is situated in a horizontal plane in the line which divides into two equal halves the angle 9 formed between the two extreme positions of the counterweighted lever (Fig. 3).

In the form of construction shown in Fig. 3 the hollow body 4 is closed at the open top end by the freely suspended regulating plate 1 and has no tubular sockets but only 90 an orifice 17 in one side which opens into a narrow channel 18 to be inserted into the air channel or flue. The hollow body 4 is in this case subdivided by a horizontal partition 19 which has an aperture 39 in the part extending through the hollow body 4. This aperture is closed by a plate 31 rigidly connected with the draft regulating plate 1 so that, when said draft regulating plate 1 is in the closed position shown in Fig. 3 95 in full lines, the plate 31 is standing at some distance above the partition 19, the aperture 39 in this partition 19 being uncovered. When however the draft regulating plate 1 is in the open position moved into the hollow body 4 (as shown in dotted lines in Fig. 3) the plate 31 covers the aperture in the partition 19.

The counterweight 6 is adjustably mounted on the arm 3 of the pivoted lever 2, 3 110 and with this object in view it has preferably a nut shaped upwardly directed ex-

tension screwed upon a screw spindle 21 rotatably located in the arm 3 of the lever. At the outer end of the screw spindle 21, a hand wheel 20 is arranged by means of which the spindle can be rotated to adjust the position of the counterweight with reference to the fulcrum 8 of the lever.

A plumb line 22 (Fig. 1) serves to indicate whether the hollow body 4 is in the vertical position. Any other suitable device may be used instead of the plumb line.

In order to mount the pivoted lever so that it oscillates with the minimum friction a cross axle 24, 25 (Fig. 5), which has a knife edge 23 on the lower surface, is preferably used as fulcrum and journaled in correspondingly formed bearings 26 on arm 27 of the hollow body 4. The regulating plate 1 is preferably suspended from the pivoted lever 2, 3 so that the friction is reduced as much as possible, for instance as shown in Fig. 4 by means of a knife edge 28 on the lower surface of the upper cross bar 29 of lug 7, said knife edge engaging 28 with a notch 30 in the end of arm 2 of the counterweighted lever 2, 3.

In the hollow body 4 a vertical partition 37 is arranged as shown in Fig. 2 which is of such a height that when the regulating plate 1 is in the closed position a passage 38 is left free between the plate 1 and the upper edge of partition 37. When this regulating plate 1 is in the open position (shown in Fig. 2 in dotted lines) this plate rests upon the upper edge of partition 37.

I claim:—

1. A draft regulator for air channels, flues and the like, comprising in combination a hollow body open at the top end to be inserted in an air channel or flue so that the air current traverses said hollow body, a freely suspended regulating plate in said hollow body exposed to the atmospheric pressure and designed to close the opening of said hollow body in accordance with the difference between the atmospheric pressure and the draft in the flue, a partition fixed in said hollow body parallel to said regulating plate and having an aperture which communicates with the air channel or flue, a plate parallel to said regulating plate arranged below said regulating plate and above said partition, a rod for rigidly connecting said plate with said regulating plate so that the aperture in said partition is closed by said second plate when the regulating plate uncovers the opening in the top part of said hollow body but uncovered when said regulating plate closes the opening in the top part of the hollow body.

2. A draft regulator for air channels, flues, and the like comprising in combination a casing in line with the flue or channel and through which the main draft passes, said casing being open at one end and communi-

cating with said air channel, flue or the like and having an air inlet or opening, a freely suspended regulating plate in said casing exposed to atmospheric pressure and adapted to open and close the air inlet or opening of the casing in accordance with the difference between the atmospheric pressure and the air pressure in said air channel, flue, or the like, counterweighted means arranged outside of said casing and from which the said regulating plate is suspended so that it is balanced in any position, and means for varying the resistance of the regulating plate to the difference in the air pressure.

3. A draft regulator for air channels, flues and the like comprising in combination a casing consisting of a hollow body and an extension forming an enlargement of the hollow body and having a lateral opening 85 at one end communicating with said channel, flue or the like, said casing having an air inlet or opening at the opposite end, a freely suspended regulating plate in said casing exposed to atmospheric pressure and adapted to open and close the said air inlet or opening of said casing in accordance with the difference between the atmospheric pressure and the air pressure in said air channel, flue or the like, counterweighted 95 means arranged outside said casing and from which said regulating plate is suspended so that it is balanced in any position and means for varying the resistance of the regulating plate to the difference in 100 the air pressure.

4. A draft regulator for air channels, flue and the like comprising in combination a casing consisting of a hollow body and an extension forming an enlargement of the hollow body and provided at one end with a lateral opening, said casing having an air inlet or opening at the opposite end, a freely suspended regulating plate in said casing exposed to atmospheric pressure and adapted to open and close the air inlet or opening of said casing in accordance with the difference between the atmospheric pressure and the air pressure in said channel, flue or the like, counterweighted means arranged outside of the casing and from which said regulating plate is suspended so that it is balanced in any position, means for varying the resistance of the regulating plate to the difference in the air pressure, a partition dividing said casing into two parts and arranged parallel with said regulating plate and having an aperture which communicates with the air channel or flue, a plate parallel to said regulating plate and arranged below said regulating plate and above said partition, a rod rigidly connecting said second mentioned plate with the regulating plate so that the aperture in said partition is closed by said second mentioned 125

plate when the regulating plate uncovers the air inlet or opening and is uncovered when the regulating plate closes the air inlet or opening.

between the atmospheric pressure and the air pressure in said air channel flue or the like, a lug projecting upwardly from the center of the regulating plate, a lever pivotally mounted on the exterior of said casing and connected at its inner end with the said lug and a counterweight adjustably mounted on the outer end of said lever to balance said regulating plate in any position.

In testimony whereof I affix my signature.

GUSTAV KORNGIEBEL.

- 5 5. A draft regulator having air channels, flues and the like comprising in combination a casing open at one end and communicating with said air channel, flue or the like and having an air inlet at the opposite end, a
10 freely suspended regulating plate in said casing exposed to atmospheric pressure and adapted to open and close the said air inlet or opening in accordance with the difference
